DEFECT FINDER AND STOP FOR CIRCULAR
KNITTING MACHINESAlbert F. Berthold, Pottstown, Pa., assignor of
fifty per cent to Carson C. Potter, Pottstown,
Pa.

Application May 7, 1941, Serial No. 392,362

4 Claims. (Cl. 66—166)

My invention relates to improvements in circular knitting machines, and particularly to an improved arrangement of defect finder and stop, characterized by simplicity of construction and action.

Another important object of my invention is to provide an arrangement of the character indicated which may be made either in the form of an attachment for existing circular knitting machines of either the stationary or revolving head type or built-in.

Other important objects and advantages of my invention will be apparent from a reading of the following description taken in connection with the appended drawings, wherein for purposes of illustration I have shown a preferred embodiment of my invention.

In the drawings:

Figure 1 is a general schematic view showing a conventional form of circular knitting machine with a rotary spindle and showing the invention incorporated therein.

Figure 2 is a top plan view of the embodiment.

Figure 3 is an enlarged fragmentary top plan view of the embodiment showing the same in set position in full lines and in tripped position in dotted lines.

Figure 4 is a bottom plan view of the feeler carriage showing the knock-off bar in set position.

Figure 5 is an enlarged longitudinal vertical sectional view taken alongside of the feeler carriage and through the adjustable arm, showing the knock-off bar in set position.

Figure 6 is a somewhat enlarged view similar to Figure 5 but showing the knock-off bar in tripped position.

Figure 7 is a transverse vertical sectional view taken through the left hand portion of Figure 5 and showing in left hand end elevation the feeler carriage and knock-off bar.

Figure 8 is a transverse vertical sectional view taken through Figure 5 along the line 8—8 and looking toward the left in the direction of the arrows.

Figure 9 is a perspective view of one of the feelers.

Figure 10 is a top perspective view of the knock-off bar.

Figure 11 is a group perspective view of the components of the adjustable bar.

Figure 12 is an enlarged transverse vertical sectional view taken through Figure 5 along the line 12—12.

Figure 13 is a transverse vertical sectional view

taken through Figure 2 along the line 13—13 and looking toward the left in the direction of the arrows, showing the tripped position.

Figure 14 is a view similar to Figure 13 but showing the set position.

Figure 15 is a horizontal sectional view taken through Figure 14 along the line 15—15 and looking upwardly in the direction of the arrows.

Figure 16 is a perspective view of the plunger. Referring in detail to the drawings, the numeral 5 generally designates a conventional form of circular knitting machine having a stationary head 6 and a rotating spindle 7, with the knitted goods 8 depending in tapering cylindrical form from below the head 6 in concentric relation to the spindle 7. In accordance with the present invention a stud 9 is threaded into the lower end of the spindle 7, the stud rising from a spacing boss 10 to the bottom of which is mounted the 10 horizontal cross arm 11 to the outer ends of which is fixed the ring 12 concentric with the axis of the spindle 7. A set bolt or stud 13 traverses a diametrically elongated slot 14 in the generally rectangular plate 15 forming the base 16 of the feeler carriage with a substantial portion 20 of the said base projecting beyond one side of the cross arm 11 as clearly shown in Figure 3 of the drawings.

Mounted slidably in apertured lugs 16, 17, and 30 18, depending from the bottom of the offset side of the plate 15 is the squared shank 19 of the knock-off bar which is generally designated 20 and which includes the bill or hook-shaped arm 21 which points in the direction of rotation of the ring 12. The shank 19 has a reduced portion 22 working through the lug 18, with an expanding spring 23 and a shoulder at the end of the reduced portion as indicated in Figure 4 of the drawings, whereby the knock-off bar is projected in a radially outward direction into the dotted line position shown in Figure 3 of the drawings when the tongue 24 of the feeler carriage is withdrawn from the notch 25 cut on the side of the shank 19. Stop pins on the shank 19 of the knock-off bar are located on opposite 40 sides of the lug 18.

The feeler carriage tongue 24 depends from one end of a U-shaped frame 28 and depends through the hole 29 formed in the base plate 15, the bight portion of the frame 28 being pivotally mounted by a shoulder bolt 30 on a raised block 31 on the top of the base plate 15 adjacent the outer end of the offset portion of the said base, the opening 29 in the base being sufficiently laterally elongated to allow sufficient pivoting

of the frame 28 on the bolt 30 to engage and disengage the tongue from the notch 25 in the shank of the knock-off bar. A spring bar lying along the top of the base plate 15 has the portion 34 engaged with one side of the bight portion of the frame 28 as illustrated in Figures 3 and 6, with the opposite end of the spring engaged with an anchor 33 so that the tendency of the frame 28 is to be swung in a left hand direction as seen in Figure 3 or turn in a counter-clockwise direction on its pivot 30.

Slidably mounted one above the other in slots in the vertical arms of the U-shaped frame 28 are the feelers 35 which have reduced fingers 36 at their radially outward ends and laterally turned lugs 37 on their opposite ends, the latter being for retaining engagement with individual leaf springs 38 mounted in vertical and horizontal alignment with the individual feelers on a post 39 secured as indicated by the numeral 40 to the extreme offset edge of the base plate 15. The leaf springs have hooks 41 at their ends for engagement in the notches 42 of the feelers 35 so that the feeler springs 43 circumscribed on the feelers between the inner vertical arm of the frame 28 and the stops 44 on the feelers can project the feelers to their operative positions as shown in Figure 5 of the drawings only after the frame 28 has been pivoted in a counter-clockwise direction so as to release the hooks on the springs from the notches in the inner ends of the feelers.

A C-shaped jaw 45 has a clamping bolt 46 in its lower arm to engage the bottom of the table 8 in opposition to the upper arm to clamp the jaw on the table with its depending body 47 mainly below the table and comprising a reduced shaft 48 which passes downwardly through the cylindrical portion 49 of the trip base 50 which projects in the substantially tangential position illustrated in Figure 2 of the drawings. The cylindrical portion 49 has a set screw 51 penetrating it for engagement with the shank or shaft 48 to lock the trip base in the desired adjusted position.

The elongated flat adjustable arm 52 comprises the plain bar 53 pivoted to the underside of the trip base 54 and extending therefrom in a generally radially inward direction as illustrated in Figure 2 of the drawings. Slidably mounted on the bottom of the plain bar 53 is the slotted bar 55 which has an upright 57 at its radially inward end, bolts 56 traversing the slots to clamp the bar 55 in adjustable extension of the bar 53. Other bolts traverse the slot in the upright 57 and holes in the curved finger 59 to enable vertically adjusting the finger 59 into the plane of swing or rotation of the knock-off bar. The helical contact arm spring 60 is stretched between a radially inward point on the adjustable bar and a point on the trip bar plate illustrated in Figure 2 normally hold the adjustable bar in engagement with the outer side of the knitted material 8 in a proper position to be engaged, through the material by the knock-off bar.

The spring 60 ordinarily holds the radially outward end of the adjustable bar in the groove 61 of the plunger which is generally designated 62 and which is vertically slidably mounted in an opening in the trip base 50 as illustrated in Figures 13 and 14, with the large shoulder 63 positioned above the base 50 as shown in Figure 14, in the set position. A head 65 on the upper end of the plunger rests on the top of bifurcations 64 on the ends of the lifting lever 66 which is pivoted as indicated by the numeral 67 in a slot 68 in the top of the standard 69 which has a stud 75

78 passing through the trip base 50 and secured by a nut 70. A contractile spring 72 is stretched between the said end of the lever 66 on the base 50 to normally depress the lever 66.

5 A relatively heavy helical expanding spring 73 is circumscribed on the lower part of the plunger between the boss 74 on the bottom of the base 50 and a stop washer 75 which is held in place by a pin 76, the lower end of the plunger resting 10 on the stop lever 77 already existent on the knitting machine and which must be depressed by the action of the plunger 62 to stop the knitting machine. The outer end of the adjustable bar 52 works in a slot 78 formed in the boss so as to drop into the peripheral notch 61 in the plunger when the plunger moves to the elevated set position shown in Figure 14.

When the adjustable bar 52 is withdrawn from the peripheral notch 61 in the plunger the spring 73 expands and depresses the stop lever 77 and halts the operation of the knitting machine. To reset the plunger 62 it is necessary only to depress the free end of the lever 66 until the plunger reaches the position shown in Figure 14.

25 It will be understood that the ring 12 with the feeler mechanism revolves inside the cloth 8 on the spindle 7 to which it is attached. The feelers are pressed against the inside of the cloth by the feeler springs 43 so that when a hole or defect 30 in the cloth appears the point of the feeler is forced through the hole or defect, thereby pulling the carriage feeler tongue 24 out of the notch 25 in the shank of the knock-off bar, thereby allowing the spring 23 to force the knock-off bar 35 in a radially outward direction against the inside of the cloth so as to push against the adjustable arm 52, disengage the latter from the retaining relation to the plunger 62 and thereby produce 40 operation of the stop lever 77 of the knitting machine.

The feeler frame or carriage 28 is reset by pressing back the knock-off bar. The feeler carriage release springs 43 come into action when the feeler carriage 28 is in the tripped position, engaging 45 themselves in the notches in the feelers 35 and pulling the feelers back and releasing them when the tongue 24 is forced into the knock-off bar notch 25 by the feeler carriage spring.

The trip base is reset by depressing the lifting 50 lever 66 as already explained.

Although I have shown and described herein the preferred embodiments of my invention, it is to be definitely understood that I do not wish to limit the application of the invention thereto, 55 except as may be required by the scope of the subjoined claims.

Having described the invention, what is claimed as new is:

1. A defect finder and stopping device for operating the stop lever of a circular knitting machine of the type having a stationary ring and a rotary spindle depending therebelow, with the knitted tube depending from said stationary ring 60 concentrically around said spindle, a cross bar fixed at its middle to turn with said spindle, a knitted tube engaging ring fixed to the other ends of said cross bar to engage the inner side 65 of the knitted tube, a feeler assembly on said cross bar comprising a pivoted spring positioned carriage having outwardly spring pressed feelers 70 engaging the inner side of the knitted tube and arranged to project outwardly through any defect in the tube found, an outwardly spring 75 pressed knock-off bar on said cross bar, latch means normally retaining said knock-off bar in

retracted position, means operatively connecting said latch means and said carriage whereby the catching of a feeler in the defect pivots said carriage and releases said knock-off bar to project radially outwardly from said knitted tube engaging ring, and trip means mounted on said stationary ring of the knitting machine, said trip means comprising a spring pressed element operatively engaged with the stop lever of the machine, and a swingable element to be operatively engaged by said knock-off bar through the knitted tube for stopping the machine.

2. A defect finder and stopping device for operating the stop lever of a circular knitting machine of the type having a stationary ring and a rotary spindle depending therebelow, with the knitted tube depending from said stationary ring concentrically around said spindle, a cross bar fixed at its middle to turn with said spindle, a knitted tube engaging ring fixed to the other ends of said cross bar to engage the inner side of the knitted tube, a feeler assembly on said cross bar comprising a pivoted spring positioned carriage having outwardly spring pressed feelers engaging the inner side of the knitted tube and arranged to project outwardly through any defect in the tube found, an outwardly spring-pressed knock-off bar on said cross bar, latch means normally retaining said knock-off bar in retracted position, means operatively connecting said latch means and said carriage whereby the catching of a feeler in the defect pivots said carriage and releases said knock-off bar to project radially outwardly from said knitted tube en-

gaging ring, and trip means mounted on said stationary ring of the knitting machine, said trip means comprising a spring-pressed element operatively engaged with the stop lever of the machine, and a swingable element to be operatively engaged by said knock-off bar through the knitted tube for stopping the machine, said trip means further comprising a clamp securably engaging said stationary ring, a trip base projecting horizontally from a portion of said clamp, said spring pressed element comprising a vertical plunger having its lower end engaged with said stop lever, and said swingable element comprising a bar pivoted horizontally on said trip base and normally engaging in a notch formed in said plunger to hold the plunger in elevated position.

3. The combination recited by claim 1 wherein said feelers comprise vertical spaced fingers mounted on said carriage for horizontal movement, springs operating between the feelers and the carriage to press the feelers yieldably in a radially outward direction.

4. The combination recited by claim 1 wherein said feelers comprise vertical spaced fingers mounted on said carriage for horizontal movement, springs operating between the feelers and the carriage to press the feelers yieldably in a radially outward direction, retainers on said assembly having detents engaging in notches in the feelers in the retracted positions of the feelers and only while said carriage is in an unpivoted initial position.

ALBERT F. BERTHOLD.
